UNITED STATES PATENT OFFICE.

GEORGE VINCENT STRAHAN, OF NEWARK, NEW JERSEY.

DESIGN FOR AN AUTOMOBILE-BODY.

50,537.

Specification for Design.

Patented Mar. 27, 1917.

Application filed December 1, 1915. Serial No. 64,600. Term of patent 7 years.

To all whom it may concern:

Be it known that I, GEORGE VINCENT STRAHAN, a citizen of the United States, residing in the city of Newark, in the county of Essex and State of New Jersey, have invented a new, original, and ornamental Design for an Automobile-Body, of which the following description, in connection with the accompanying drawing, is a specification.

The single figure of the drawing is a perspective view of an automobile body, showing my new design.

I claim:

The ornamental design for an automobile body, as shown.

GEORGE VINCENT STRAHAN.
